W. G. CLAYTON,
SPARKING PLUG.
APPLICATION FILED APR. 2, 1919.

Patented May 25, 1920.

Inventor
William George Clayton
by his Attorney *Lawrence Jaquier*

UNITED STATES PATENT OFFICE.

WILLIAM GEORGE CLAYTON, OF MELBOURNE, VICTORIA, AUSTRALIA.

SPARKING PLUG.

1,340,878.

Specification of Letters Patent. Patented May 25, 1920.

Application filed April 2, 1919. Serial No. 286,982.

To all whom it may concern:

Be it known that I, WILLIAM GEORGE CLAYTON, a subject of the King of Great Britain, and resident of 47 Queen street, 5 Melbourne, in the State of Victoria, Commonwealth of Australia, have invented a certain new and useful Improved Sparking Plug, of which the following is a specification.

10 This invention relates to an improved sparking plug and has been devised in order to provide a plug of considerably greater utility than those at present in use.

The sparking plugs at present in use are 15 defective in that should one of the contact points become clogged or otherwise close the spark gap, a short circuit to earth is created and the whole of the sparking points of each plug becomes inoperative and the particular 20 cylinder of the engine is rendered useless until the circuit is readjusted. In some cases a plurality of plugs are fitted to each cylinder to overcome to some extent the existing constructional defects of the plugs.

25 This invention has been specially devised in order to overcome these defects and to provide a sparking plug by the use of which at least one of the contact points remains in operative condition irrespective of the clogging or bridging of any or all of the other 30 spark gaps in the plug circuit.

The essential features embodied in the invention are as follows:—

1. The arrangement of the circuit so that 35 should one or more gaps be short circuited, the remaining gap or gaps remain in open circuit and therefore in sparking operation.

2. The arrangement of varying distanced 40 spark gaps in the circuit so that sparks of varying intensity are created to insure advantage of power, easy starting, and a rapid explosion, while at the same time carbon deposits are reduced to a minimum.

3. The arrangement of the circuit and the 45 means employed for insuring positive sparking irrespective of the choking of one or more of the spark gaps in the circuit, provided one gap is left clear for sparking.

The basic principle underlying the 50 invention consists of means whereby a continuous circuit is insured through the spark

plug irrespective of the choking or bridging of the spark gaps, provided of course, one spark gap is left clear for sparking purposes, the circuit being so arranged that the 55 leads carrying or formed with the contact points are sufficiently close together as to insure the bridging of the current from the supply lead over the whole of the contact points and gaps in turn to earth on the 60 engine frame.

In carrying this principle into practical effect, one means of mounting and the circuit connected therewith will now be described.

65 In the drawings:—

Figure 1 is a view illustrating in elevation and vertical central section the preferred construction and arrangement of the sparking plug for accomplishing the object of the 70 invention.

Fig. 2 is an enlarged view in vertical central section of the improved sparking plug.

Fig. 3 is a view in underside plan of 75 Fig. 2.

According to this invention a sleeve or shell 1 of the plug is provided at its lower end with a threaded portion 2 for fitting into the cylinder and in the body of the 80 sleeve 1 a nut 3 is provided. Through the plug sleeve or shell 1 is a porcelain or other plug of insulating material 4 extending a sufficient distance past the top of the sleeve or shell as illustrated to obviate any short 85 circuit between the plug and the engine frame which forms the earth of the circuit. Leading to the porcelain plug 4 from the magneto in the usual way is the lead wire 5 which preferably connects the terminal 90 point by a nut 6 threaded to the contact lead 7 which projects diagonally within the plug and at its lower end is slightly bent inwardly to form a contact point 8 of the first spark gap 9 in the plug 1.

95 This contact lead 7 is preferably provided along substantially the whole of its length with a covering of insulation 10 as illustrated more particularly in Fig. 2.

In the construction illustrated a short distance from the first contact point 8 is another contact point 11 formed on a hori-

zontal or curved member 12 of an inverted T piece or contact wire or member 13 to form the first spark gap 9 while the vertical portion of the inverted T member 13 extends to and is embedded in the insulation 4 of the plug 1.

The opposite end of the horizontal member of the first T piece 13 forms a further contact point 14 for another or second spark gap 15 the other contact of which is adjacent therewith and may consist of another inverted T member 13 or may comprise the contact end of the wire leading to earth or the engine frame. In the construction illustrated, four spark gaps are shown therefore three inverted members 13 are employed showing the spark gaps 16 and 17, the contact 18 being formed on the end of the wire 19 which is embedded in the plug shell 1 as 20 illustrated in Fig. 2.

The spark gaps are preferably arranged within the lower portion 2 of the shell 1, a bridge 23 being preferably formed to receive the contact members while gas spaces 24 are 25 provided on either side of the bridge 23.

It will thus be obvious that a plurality of spark gaps may be arranged in line or in any other suitable way provided the circuit is continuous by bridging the gaps in turn 30 from the inner lead to the earth wire therefore two or more spark gaps may be employed in a plug with the intermediate spark gap contact members of inverted T or other shape embedded in the insulation in the manner above described.

The preferred arrangement of the contact lead 7 consists in forming the upper end with a thread to receive the nut 6 which locks the end of the lead 5 to a block 21 40 adapted to thread or fit tightly into the top of the insulation 4 the contact lead 7 being formed or fitted with projections 22 adapted when the nut 6 is tightened to clamp against the underside of the block 21 and the lead 7 is thus held rigidly in position.

I desire it to be understood that the plug 1 may be of any suitable construction and any suitable insulation in lieu of the porcelain above described may be embodied, furthermore, any number of spark gaps adapted to receive the spark in turn by the current bridging the spark gaps in rotation from the main lead wire from the source of supply to earth may be embodied without departing 50 from the spirit and scope of the invention.

A spark plug constructed and arranged in a circuit as above described will be of great utility particularly for the reason that a greater advantage is obtained owing to the 60 fact that one or more of the spark gaps may be short circuited or bridged, by carbon or other material, yet provided one gap is clear for sparking, the plug will spark, the contacts of the gaps being arranged sufficiently 65 closely together to insure the bridging of the

circuit across all the contacts from the main lead to the earth wire as above described.

What I claim as my invention and desire to secure by Letters Patent is—

1. In a sparking plug, a metal shell and a 70 plug of insulating material extending above said shell and at its lower end substantially level with the bottom of the shell, a conductor in said insulation, extending at an angle to the bottom of the plug, said insulating 75 material formed at its lower end with an angular recess cut a substantial distance away from the shell on the side having the positive contact, a bridge, spark points in said bridge forming spark gaps therebetween, and a contact to the shell, gas spaces being formed within the plug on either side of the bridge.

2. The combination of a sparking plug having a positive terminal and a plurality of 85 intermediate spark points arranged to spark in series from the positive terminal to earth, a plug of insulation, and a bridge formed on the plug of insulation, said bridge being removed, a substantial distance from the side 90 of the plug shell adjacent the positive terminal, the intermediate points from the positive to earth being embedded in said bridge, substantially as described.

3. In a sparking plug a plurality of spark 95 points, a positive terminal, an insulating plug member formed with a recess therein, a shell surrounding said plug member, a bridge formed in the plug within the recess, the lower face of said bridge extending at an 100 angle to the bottom of the shell and disposed a substantial distance from the shell of the plug, the spark points forming spark gaps being embedded in and extended from the bridge and into the recess, substantially as 105 described.

4. In a sparking plug and in combination, a spark plug shell, an insulated core, a positive lead, an earth lead, said core formed with a recess, a bridge in the core within the 110 recess, said core formed with gas spaces on either side of said bridge, and spark points extended from the bridge and into the recess so as to form a plurality of spark gaps between the positive and the earth leads. 115

5. In a sparking plug and in combination, a metal shell constituting a negative electrode, an insulator in the negative electrode, a positive electrode extending through said insulator, and terminating at a point in 120 proximity to said shell and off-set from the center of said insulator, a plurality of separate spark points between the positive electrode and the negative electrode, and a portion of said insulator preventing short-circuiting between the positive electrode and the nearest portion of the negative electrode. 125

6. In a sparking plug and in combination, a metal shell constituting a negative electrode, a positive electrode, a plurality of 130

spark points between the positive electrode and the shell, and an insulator contained in said shell and having an angular face, said positive electrode extending into the lower portion of said angular face, and the aforesaid contacts being arranged angularly along the angular face of said insulator.

7. A sparking plug according to claim 6, having more than two intermediate spark points between the positive and negative

electrodes and extending over substantially the entire face of the insulator.

Signed at Melbourne, in the State of Victoria, Commonwealth of Australia, this 30th day of January, 1919.

WILLIAM GEORGE CLAYTON.
